UNITED STATES PATENT OFFICE.

HARRY J. DRAKE AND EDWARD E. HALL, OF BUSHNELL, ILLINOIS.

STOCK-TROUGH.

No. 906,396.

Specification of Letters Patent.

Patented Dec. 8, 1908.

Application filed May 19, 1908. Serial No. 433,781.

To all whom it may concern:

Be it known that we, HARRY J. DRAKE and EDWARD E. HALL, citizens of the United States, residing at Bushnell, in the county of McDonough and State of Illinois, have invented certain new and useful Improvements in Stock-Troughs; and we do hereby declare the following to be a full, clear, and exact description of the invention, such as will enable others skilled in the art to which it pertains to make and use the same.

This invention relates to new and useful improvements in stock troughs and has relation more particularly to a trough that can be used either for feeding or watering purposes.

It is a further object of the invention to provide a device of this character formed of but few parts that may be readily applied in position to produce a finished article.

It is furthermore an object of the invention to provide a device of this character which will dispense with heavy material and be simple in construction, efficient and advantageous in practice and comparatively inexpensive to manufacture.

With the above and other objects in view the invention consists of the details of construction and in the novel arrangement and combination of parts to be hereinafter referred to.

In describing the invention in detail reference will be had to the accompanying drawings forming part of this specification, wherein like characters of reference denote corresponding parts in the several views, and in which,

Figure 1 is a view in perspective illustrating the invention. Fig. 2 is a view in perspective, detached, of one of the end plates employed in the invention. Fig. 3 is a fragmentary view in perspective illustrating the body or trough portion. Fig. 4 is a view in perspective, enlarged, of a corner of the device. Fig. 5 is an enlarged fragmentary view in elevation illustrating a detail of the invention, and, Fig. 6 is a fragmentary view in section illustrating further details. Fig. 7, is a fragmentary sectional view illustrating a detail of the end plates.

In the drawings 1 denotes the body portion of the invention which is formed preferably of a plate of steel curved into a semi-cylindrical form in cross section, having the outwardly extending longitudinal flanges 2 at its top and the depending flanges 3 at its

ends. The top flanges 2 are bent back upon themselves as at 3' (Fig. 6) which gives strength to the top of the trough, thus obviating the necessity of employing independent or auxiliary means. The end flanges 3 at intervals are slit in order to produce double tenons 4.

Employed in conjunction with the body portion 1 are the end plates or supports 5. Each of these plates is rectangular in shape and is provided with the inwardly extending longitudinal flanges 6 and the end flanges 7, the upper flange 6 being bent upon itself as at 8 for the same purpose as referred to with reference to the flanges 2. The lower flange 6 is provided with openings 9 for the passage of suitable securing or anchoring means if desired.

In assembling the device the double tenons 4 of the body 1 are inserted through slots 10 in the end plates 5 and the said tenons are then separated, one being bent in one direction and the other in an opposite direction, as is more particularly shown in Fig. 5. They are then soldered as indicated in Fig. 1. The upper flanges 2 of the body 1 are opposed against the upper flanges 6 of the end plates 5 and said flanges 5 and 6 are securely held one to the other by the rivets or other fastening means 11. The contacting portions of the body 1 and the end plates 5 are then soldered one to the other as are also the contacting portions of the flanges 2, 6 and 7. The flanges 2 are connected by a transverse brace 12 positioned approximately centrally of the body 1. This brace serves to reinforce the body and also acts as a divisor of the drinking or feeding space.

What we claim is:

In a device of the character described, the combination of a body having top flanges and end flanges, end plates, each of said end plates being provided with top and bottom flanges, the top flanges of the end plates being secured to the top flanges of the body, the lower flanges of the end plates being perforated, and means whereby the end flanges of the body engage the end plates.

In testimony whereof we have signed our names to this specification in the presence of two subscribing witnesses,

HARRY J. DRAKE.
EDWARD E. HALL.
